UNITED STATES PATENT OFFICE.

LOUIS R. HAGEN, OF MINNEAPOLIS, MINNESOTA.

BOX-SEAL CUTTER.

1,109,286.

Specification of Letters Patent.

Patented Sept. 1, 1914.

Application filed January 15, 1914. Serial No. 812,235.

To all whom it may concern:

Be it known that I, LOUIS R. HAGEN, a citizen of the United States, residing at Minneapolis, in the county of Hennepin and 5 State of Minnesota, have invented certain new and useful Improvements in Box-Seal Cutters; and I do hereby declare the following to be a full, clear, and exact description of the invention, such as will enable others skilled in the art to which it 10 appertains to make and use the same.

My invention has for its object to provide a box seal cutter, especially adapted for use in cutting the seals of snuff boxes.

15 As is well known, a large number of boxes have their covers secured in position by a seal of paper pasted over the joint between the box and the telescoped flange of its cover, and secured partly to said box and 20 partly to the flange of said cover.

To the above end, generally stated, the invention consists of the novel devices and combinations of devices hereinafter described and defined in the claims.

25 In the accompanying drawings, which illustrate the invention, like characters indicate like parts throughout the several views.

Referring to the drawings:—Figure 1 is 30 a plan view of the improved box seal cutter, some parts being broken away, and some of the exposed parts being shown in section; Fig. 2 is a vertical section taken on the line $\alpha^2 \alpha^2$ of Fig. 1, and showing a box 35 mounted in a position to have its seal cut; and Fig. 3 is a transverse section taken through the box, shown in Fig. 2, some parts being broken away, and also showing a portion of the seal cutting knife.

40 The numeral 1 indicates a base having a socket 2 for receiving the top portion of a box. The bottom of this socket 2 is open and is formed by an annular flange 3 integral with the base 1. As shown, the base 45 1 is preferably made from cast metal and is quite heavy, so as to prevent the same from being easily moved when on a counter or show-case.

Working through an opening 4 in the side

wall of the base 1 and into the socket 2 is a 50 horizontally extended knife 5, integrally formed at the intermediate inner edge of a horizontally extended lever 6. This lever 6 is intermediately pivoted at 7 between a pair of vertically spaced bearing lugs 8, cast 55 integral with the base 1. One of these lugs is located above and the other below the opening 4, through which the knife 5 works.

The short end of the lever 6 is bent laterally toward the base 1, to afford a stop 9, 60 which normally engages the base 1. A sear spring 10 normally holds the lever 6 in a position with its knife 5, which is on its long end, retracted. This spring 10 is mounted on the pivot pin 7 of the lever 6, 65 and one end thereof reacts against the base 1, and the other end thereof is anchored to the long end of the lever 6. A finger piece 11 is cast integral with the base 1.

In Fig. 2 is shown an inverted box Z having a cover Z¹, mounted in the socket 2 in a position to have its seal Z² cut by the knife 5. To cut the seal Z², the finger piece 11 is engaged by the thumb, and inward pressure is applied to the long end of the lever 6 by the index finger. This inward pressure on the lever 6 will carry the knife 5 70 into the socket 2 and force the same through the seal Z². By holding the knife in this position and rotating the box Z in the socket 75 2, the seal Z² may be completely severed where the flange of the box cover joins the box, as best shown in Fig. 3.

The above described device, while extremely simple, and of small cost, is thought 80 85 to be highly efficient for the purpose had in view.

What I claim is:—

1. The combination with a base having a box-receiving socket with an opening in its 90 wall, of a lever intermediately pivoted to the outer wall of said base, one end of said lever normally engaging said base and acting as a stop, a knife on the other end of said lever working through said opening 95 into said socket, and a spring operative on said lever, to normally hold said knife retracted.

2. The combination with a base having a box-receiving socket with an opening in its wall, of a lever intermediately pivoted to and between a pair of bearing lugs on the outer wall of said base, one end of said lever normally engaging said base and acting as a stop; a knife on the other end of said lever working through said opening into said socket, and a spring operative on

said lever, to normally hold said knife re- 10 tracted.

In testimony whereof I affix my signature in presence of two witnesses.

LOUIS R. HAGEN.
